HAIR SINGEING TORCH

Antonio Bongiovanni and Onofrio Zacamy,
Philadelphia, Pa., assignors of one-third to
Salvatore Gaglione, Collingdale, Pa.

Application August 20, 1932. Serial No. 629,714

7 Claims. (Cl. 67—22)

This invention is intended to provide a novel and improved torch device for the use of barbers in singeing hair, its objects being the production of a very light and slender element of requisite strength and rigidity adapted to burn slowly with a clear steady flame and having safety extinguishing as also self-lighting features rendering it particularly applicable to the stated purpose.

10 Various kinds of burners and torches have of course been produced and used for various purposes, but few of these are really adapted or safe for use in the delicate and somewhat dangerous operation of singeing hair because of cumbrousness, too large or hot, or else too flaring and uneven a flame and other well recognized reasons. Such as are generally used for the purpose very often burn too rapidly or wilt and drop pieces or residue which may fall onto the

15 subject's neck or down his clothing with serious consequences, so that no really satisfactory burner has yet been devised for this particular purpose. It is these defects and objections which the torch here set forth is designed to eliminate

20 insofar as possible, as also to provide a more convenient article.

The invention will be best understood by further description with reference to the accompanying drawing, illustrating a practicable embodiment thereof.

In said drawing:

Fig. 1 is a longitudinal elevation of the burner element as partially formed, showing inner component parts in separated relation exposed by a

35 broken away portion at one end;

Fig. 2 is a similar view representing the partially formed element intact for burning;

Fig. 3 is a like view showing the element with applied means for self-lighting;

40 Fig. 4 is a sectional view on the line 4—4 of the preceding figure; and

Fig. 5 correspondingly illustrates the completely formed burner element.

Referring to the several views, a stem-like torch adapted to burn from end to end is represented by the taper 6. This, formed preferably in a length substantially equal to that shown, comprises a plurality of cotton strands 7 arranged end to end, either with or without twisting together, in the form of a wick. These strands, of which are six in this instance, are of very loose twist so as to burn easily and are advantageously saturated or coated with a spermaceti before arranging together for the triple purpose of increasing their burning property,

causing them to adhere more readily or tenaciously to each other and adding a certain rigidity thereto.

These strands so arranged in a wick formation are embedded within a body 8 of wax or tallow therewith forming the core of the taper, such wax or tallow being well hardened and having only enough oily-fat content to melt or burn away slowly and evenly as the strands themselves are fully consumed. The leaving of residue or charred ends of wick and the formation of globules of excessive oil resulting from incomplete consumption of both while burning and which might drop upon the subject's neck or clothing are thus substantially eliminated, making it perfectly safe to hold the lighted end close to the head.

Around the core formed by said strands and wax or tallow body, a protective coating 9 of paraffin is applied, this paraffin being adapted to melt away at the same rate as the wax or tallow. The whole may advantageously be worked or rolled to firmly compress the parts together. A slender burner element is thus formed, which will be adequately strong and rigid as result of the hardening of the wax or tallow and paraffin coatings over the cotton strands, to which added rigidity is imparted, as aforesaid, by saturating or coating the same with a spermaceti. In use as intended therefore, there is little change of breakage or cracking, although a sufficient strain will of course weaken or rupture it because of the brittle nature of the wick-encompassing parts.

For convenience in lighting this torch or taper, the same is tipped in this instance at both ends with a head 10 of a hardened combustible composition that is ignited by friction, such head being preferably of a substance or component ignitable only by scraping against a particular kind or material of surface like the ordinary "safety match". This is done simply by dipping the ends in a solution of the substance, the exact character and ingredient of which is merely incident to the invention so that none is specifically named. In addition to the convenience, this feature affords a safety advantage to the user since it eliminates the necessity of lighting by match or separate flame which might become a fire hazard if not thereafter disposed of or carefully extinguished. If desired, an additional number of these igniting heads in the form of beads might be applied at intervals along the length of the taper for re-lighting it at such intervals after burning only partially away, but this

would be unnecessary and even somewhat dangerous for the use here intended, because a full half of the taper will be consumed in the ordinary hair-singeing operation.

- 5 At the center of the torch, a thin metal sleeve 11 of approximately one inch length is applied therearound to hold without slipping in either direction, the same being advantageously of split form as represented for convenience in applying 10 direct rather than over the end. This sleeve, functioning primarily to choke or snuff out the flame when the taper has burned half-way down and so providing a safety-extinguishing means, serves also as a holder for manipulating the torch 15 in use without softening the paraffin by body warmth or transmitting any of its oily substance to the fingers.

The novel and improved burner element thus produced for the stated purpose has decided advantages which will be quickly recognized by barbers and hair treaters having occasion to use the same, not only for the practical convenience afforded by the self-lighting feature, but also and more particularly for the described safety features it possesses over the ordinary torch device. It burns as aforesaid with a low, clear and steady flame and with a complete consumption 25 of the inflammable parts, so that there can be no spluttering or flaring nor any dropping of residue particles or wax as characteristic of ordinary tapers or devices of this kind.

Having thus described our invention, what we claim as new and desire to secure by Letters Patent of the United States is:

- 35 1. A hair singeing torch, comprising a plurality of cotton strands embedded in a body of wax coated over with paraffin and together forming a long slender inflammable member, combustive material ignitable by friction on the ends of the member, and a metallic sleeve serving to extinguish the flame applied around the middle part of said member.

- 40 2. A hair singeing torch, comprising a plurality of loose-twist cotton strands arranged together end to end, a body of hardened wax encompassing the strands, a coating of paraffin around said body; said strands, wax body and paraffin coating together forming an inflammable and semi-rigid stem-like member of slender proportions, heads 45 of a combustive composition ignitable by friction applied to the ends of said member for self-lighting purposes, and a thin metallic sleeve secured around the middle part of the member to snuff out its flame when burned half-way down.

3. A hair singeing torch, comprising a plurality of cotton strands embedded together end to end in a body of wax of limited oily-fat content in formation of a semi-rigid stem member of slender proportions, tippings of a hardened combustible composition ignitable by friction on the ends of said member for lighting the same, and a thin metal sleeve applied around the middle part of the member for extinguishing its flame when burned down to a half-way point.

4. A torch member comprising a plurality of cotton strands arranged together end to end in a wick formation, a body of hardened wax or tallow of limited oily-fat content encompassing said strands and therewith forming a substantially rigid stem-like member inflammable along its length, tippings of a hardened combustible material ignitable by friction on the ends of said member for lighting the same, and a thin metal sleeve applied around the middle part of the member for extinguishing the flame thereof when burned down to a half-way point.

5. A hair singeing torch, comprising a plurality of cotton strands embedded together end to end in a body of wax or tallow of limited oily-fat content in formation of a substantially rigid stem-like member inflammable along its length, heads of a combustive composition ignitable by friction applied to the ends of said member for lighting the same, and a thin metallic sleeve secured around the middle part of the member so as to extinguish the flame thereof when it has burned down to a half-way point.

6. A torch member comprising a plurality of cotton strands arranged together end to end in a wick formation, a body of hardened wax or tallow of limited oily-fat content encompassing said strands and therewith forming a substantially rigid stem-like member inflammable along its length, and tippings of hardened combustible material ignitable by friction on the ends of said member for lighting the same.

7. A hair singeing torch, comprising a plurality of cotton strands embedded together end to end in a body of wax or tallow having a limited oily-fat content in formation of a substantially rigid stem-like member inflammable along its length, and heads of a combustive composition ignitable by friction applied to the ends of said member for self-lighting the same from either end.
